UNITED STATES PATENT OFFICE.

EBERHARD FABER, OF PORT RICHMOND, NEW YORK.

PEN-HOLDER.

SPECIFICATION forming part of Letters Patent No. 255,961, dated April 4, 1882.

Application filed December 15, 1881. (No model.)

To all whom it may concern:

Be it known that I, EBERHARD FABER, a citizen of the United States, residing at Port Richmond, in the county of Richmond and State of New York, have invented new and useful Improvements in Pen-Holders, of which the following is a specification.

This invention relates to pen-holders of the kind known as "anti-nervous" pen-holders.

10 My invention consists in the combination, with the anti-nervous material, of a tubular support and a pin formed on the handle to fit the interior of this support, a ferrule secured to the handle above said pin projecting over 15 the inner edge of the anti-nervous material, so as to conceal and protect the same. The tip of my pen-holder is constructed with a cap which covers the outer edge of the anti-nervous material, and with a tube which fits the 20 interior of the support of said anti-nervous material.

This invention is illustrated in the accompanying drawings, in which Figure 1 represents a front view. Fig. 2 is a sectional-side 25 view. Fig. 3 is a horizontal section in the plane $x x$, Fig. 1.

Similar letters indicate corresponding parts.

In the drawings, the letter A designates the anti-nervous material, such as a thin sheet or 30 tube of india-rubber, and B is the tubular support for this anti-nervous material.

C is the staff or handle of my pen-holder, which is turned down to form a pin, a, which fits the interior of the tubular support B. On 35 the handle C, above the pin a, is secured a ferrule, b, which extends over the inner edge of the anti-nervous material, so as to conceal and protect said edge and to impart to the article a handsome finish.

40 The tip D of my pen holder forms a cap, c, which projects over the lower or outer edge of

the anti-nervous material, so as to conceal the same, and in the interior of said tip is a tubular projection, d, which fits the interior of the support B. A rivet, e, serves to secure the tip 45 D in the desired position and to connect the same firmly with the support B.

I do not claim as my invention the combination of an anti-nervous material with a pen-holder, such being well known. 50

What I claim as new, and desire to secure by Letters Patent, is—

1. The combination, substantially as herein-before described, of the anti-nervous material A, the internal tubular support, B, for the 55 same, the staff or handle C, having a projecting part extending over and surrounding the upper end of the anti nervous material to conceal and protect the edge thereof, and a flange on the tip D surrounding the lower edge of the 60 anti-nervous material, as set forth.

2. The combination, substantially as herein-before described, of the anti-nervous material, the tubular support, the handle, the pin formed on said handle and fitting the interior of the 65 tubular support, the ferrule secured to the handle and projecting over the inner edge of the anti-nervous material and the tip.

3. The combination, substantially as herein-before described, of the anti-nervous material, 70 the tubular support, the handle connected to the tubular support, the tip D, and the cap c, formed on said tip and constructed to conceal and protect the outer edge of the anti nervous material.

In testimony whereof I have hereunto set my hand and seal in the presence of two subscribing witnesses.

EBERHARD FABER. [L. S.]
